Primary Examiner — Patricia Palasik(74) *Attorney, Agent, or Firm* — Corinne R. Gorski(57) **CLAIM**

The ornamental design for a crusher, as shown and described.

DESCRIPTION

FIG. 1 is a front perspective view of a first embodiment of a crusher according to the present invention;

FIG. 2 is a front view thereof;

FIG. 3 is a back view thereof;

FIG. 4 is a right view thereof;

FIG. 5 is a left side view thereof; and

FIG. 6 is a top view thereof.

FIG. 7 is a front perspective view of a second embodiment of a crusher according to the present invention;

FIG. 8 is a front view thereof;

FIG. 9 is a back view thereof;

FIG. 10 is a right view thereof;

FIG. 11 is a left view thereof; and

FIG. 12 is a top view thereof.

The broken lines in the drawings depict unclaimed environmental subject matter.
